Primary Examiner — Susan Moon Lee*(74) Attorney, Agent, or Firm* — Nixon & Vanderhye, P.C.**CLAIM**

I claim the ornamental design for a card for electronic computer, as shown and described.

DESCRIPTION

FIG. 1 is an elevation view of a front face of a card for electronic computer in accordance with a first exemplary embodiment of my new design; and,

FIG. 2 is an elevation view of the front face of a card for electronic computer in accordance with a second exemplary embodiment.

The card is of no substantial thickness. The undisclosed sides of the card are not claimed.
